UNITED STATES PATENT OFFICE

101,049

DESIGN FOR A BOTTLE

Chester Mark, Chicago, Ill.

Application July 9, 1936, Serial No. 63,753

Term of patent 7 years

To whom it may concern:

Be it known that I, Chester Mark, a citizen of the United States, residing at Chicago, in the county of Cook and State of Illinois, have invented a new, original, and ornamental Design for a Bottle, of which the following is a specification, reference being had to the accompanying drawing, forming part thereof.

The figure shows a perspective view of a bottle embodying my new design. The opposite sides are substantially the same.

I claim:

The ornamental design for a bottle, substantially as shown and described.

CHESTER MARK.
